ROTARY CRANK-DRIVEN INTERMITTENT GRIP

Frederick A. Gruetjen, Milwaukee, Wis., assignor to A. O. Smith Corporation, Milwaukee, Wis., a corporation of New York

Application August 24, 1946, Serial No. 692,767

5 Claims. (Cl. 74—118)

1

This invention relates to a stoker drive and has particular reference to the employment of a pinch clutch for intermittently driving the feed screw of a stoker.

The principal object of the invention is to provide an efficient and durable intermittent drive for a stoker that is inexpensive to construct and assemble.

Another object is to provide a substantially quiet drive for a stoker feed screw.

Another object is to provide a novel shear pin assembly for a stoker drive.

These and other objects of the invention will appear hereinafter in connection with the following description of an embodiment of the invention illustrated in the accompanying drawings.

Figure 1 is a side elevational view of the drive of the invention with the unit at the beginning of the driving stroke;

Fig. 2 is a similar view with the unit at the end of the driving stroke;

Fig. 3 is a top plan view of the driving unit;

Fig. 4 is a section taken on line 4—4 of Fig. 3;

Fig. 5 is an elevational view of the driving drum;

Fig. 6 is a section through the drum taken on line 6—6 of Fig. 5; and

Fig. 7 is a detail section taken on line 7—7 of Figure 1.

The drawings illustrating an embodiment of the invention show a base plate 1 of a coal stoker unit to the inner end of which is secured a hopper 2 with a wall which extends vertically upward from base 1 and then turns diagonally outwardly over the base. Side walls, not shown, are secured to the hopper and to base 1 to house the driving unit of the stoker.

The bearing plate 3 is bolted to the vertically extending wall of hopper 2 directly above base 1 and receives the housing 4 of the clutch shaft 5 which extends horizontally therethrough within the bushing 6.

The inner end of shaft 5 is locked to the feed screw, not shown, to drive the same. Shaft 5 is driven from the motor and transmission assembly 7 through the connecting rod 8 and the pinch clutch drive of the invention. The motor and transmission assembly are suitably secured to base 1 at the left side thereof as viewed from Figure 1.

The pinch clutch drive has a sheet metal drum 9 which is secured to the rear end portion of clutch shaft 5 between plates 10 by the nut 11. The forward plate 10 abuts against the rear end 55 of shaft housing 4.

2

Drum 9 is formed of two half members 12 which when interlocked together provide a square central opening 13 for locking the drum to shaft 5 which is squared at the rear end complementary to the drum opening. When nut 11 is tightened the drum is held against axial movement between plates 10 and by housing 4.

The circumferential wall of drum 9 is provided with circumferential slot 14 which extends completely around the drum when half members 12 are assembled together.

The lower end of the lever arm 15 projects into slot 14 a substantial distance and is connected to the drum by pin 16 which extends transversely across slot 14 on the outside of the wall of drum 9 and by pin 17 which extends transversely across slot 14 on the inside of the peripheral wall of the drum. The pins 16 and 17 engage opposite sides of the wall of drum 9 with pin 16 set slightly ahead of pin 17 in the direction of movement of drum 9 for effective engagement of the drum to drive the same.

The outer pin 16 is held in place by clips 18 to permit ready replacement in the event of 25 shearing in service while the inner pin 17 is press fitted in place through suitable apertures in drum 9.

The upper end of lever arm 15 is pivoted to the upper end of connecting rod 8 for actuation by rod 8 when the latter is reciprocated by motor and transmission assembly 7, as will be described.

A spring 19 is attached at one end to lever arm 15 preferably to the right of the inner pivot pin 17 and the other end of the spring is connected to bracket 20 which is secured to hopper 2. Spring 19 biases arm 15 in an upwardly direction tending to pull the arm opposite the rotational direction of drum 9.

The adjustable end 21 of the stroke regulating bracket 22 which is suitably secured at the outer end to the frame, supporting hopper 2, extends diagonally within slot 14 and engages inner pin 17 to interrupt the rotary movement of drum 9 by preventing further movement of arm 15 in a clockwise direction. By adjusting end 21 inwardly or outwardly the rotary movement of drum 9 may be decreased or increased by enabling arm 15 to move in a lesser or greater clockwise movement as the case may be.

Figures 1 and 2 illustrate, respectively, the clutch assembly at the beginning of the driving stroke and after completion of the same.

As shown in Figure 1, when connecting rod 8 is reciprocated upwardly by motor and transmission 7, lever arm 15 is rotated by rod 8 in a clockwise direction. This movement of arm 15

moves the line of centers of pins 16 and 17 to substantially right angles to the circumferential wall of the drum 9 and disengages the pins from the drum wall. At the same time spring 19 pulls the lower end portion of lever arm 15 in a clockwise direction with a slight lag behind the rotary movement given the arm by rod 8, and the pins 16 and 17 carrying arm 15 in slot 14 ride freely over the circumferential wall of the drum. The clockwise movement of arm 15 continues until inner pin 17 engages end 21 of bracket 22.

When rod 8 is reciprocated downwardly by motor and transmission 7, arm 8 immediately rocks to a position where the peripheral wall of the drum is clamped between pins 16 and 17 as spring 19 tends to pull the lower end of arm 15 to the right. As arm 15 moves downwardly drum 9 is rotated in a counter-clockwise direction until the end of the stroke is reached and arm 15 is again pushed upwardly by rod 8. The rotation of drum 9 in a counter-clockwise direction continues intermittently as pins 16 and 17 clamp the drum wall in moving in a counter-clockwise direction and ride freely over the drum upon moving in a clockwise direction.

As drum 9 rotates, shaft 5 is rotated and intermittently drives the feed screw, feeding coal to the furnace from hopper 2.

In order to insure that there will be no reverse rotation of drum 9 when arm 15 is pushed upwardly and pins 16 and 17 ride freely along the drum, a second lever arm 23 is pivoted at one end to bracket 24 on base 1 of the stoker unit and the other end projects a substantial distance within slot 14.

A pin 25 similar to pin 17 of arm 15 extends transversely across slot 14 on the inside of the peripheral wall of drum 9 and the pin 26 similarly to pin 16 of arm 15 extends transversely across slot 14 on the outside of the drum wall.

Pins 25 and 26 are offset but whereas outer pin 16 is offset to the left of the center line of arm 15, the outer pin 26 of arm 23 is offset to the right of the center line. Pin 25 is offset to the left of the center line of arm 23 whereas pin 17 of arm 15 is offset to the right of the center line.

By offsetting pins 25 and 26 as described, when drum 9 is rotated from motor and transmission 7 through rod 8 and arm 15 in a counter-clockwise direction, pins 25 and 26 ride freely over the peripheral wall of the drum. However, at the end of the driving stroke pins 25 and 26 clamp the drum wall therebetween so that when the driving arm 15 and pins 16 and 17 move to the right drum 9 cannot rotate to the right with them in a clockwise direction. Shaft 5 remains stationary as does the feed screw.

The invention provides an inexpensive drive for a stoker that drives the feed screw intermittently with substantially silent operation.

The drum 9 is readily formed from two half members and keyed to shaft 5 as described. The inner pins 17 and 25 are readily inserted into their respective arms by openings provided in the sides of the drum 9 at locations suitable for locating the pins and arms.

The pin 18 of the driving unit and the pin 26 of the holding unit are readily replaceable in the event that they shear in service, which is important from the operator's standpoint.

Various embodiments of the invention may be employed within the scope of the accompanying claims.

I claim:

1. A pinch clutch actuated by a reciprocating element of a power source for intermittently rotating a stoker screw, which comprises a sheet metal tubular member concentric with said shaft and connected to the rear end of said stoker screw and having a circumferential slot extending in the circumferential wall thereof, a driving lever arm secured at one end to said reciprocating element and having the other end disposed to grip the wall of said tubular member to rotate the same when the arm is moved in one direction and to disengage said member and ride free of the same when said arm is moved in the opposite direction, and a second lever arm anchored at one end to the frame of the stoker assembly with which the clutch is employed and extending within the slot in said tubular element, a pin extending transversely through said lever arm on the inside of said tubular element, and a second pin extending transversely through said arm on the outside of said tubular element with said pins being offset to immediately grip said tubular element and prevent reverse rotation of the same when the end of the driving lever arm rides free of the drum and to ride freely over the tubular member when the same is being driven.

2. A pinch clutch stoker drive for driving a shaft from a power source through a reciprocating connecting rod to intermittently rotate a stoker screw, which comprises a sheet metal drum secured to said shaft and having a circumferential slot extending in the circumferential wall thereof, a lever arm secured at the upper end to said reciprocating rod and having the lower end extending into said drum through said slot, means at the lower end of said arm to engage the drum and rotate the same when the lever arm is rotated in one direction by said reciprocating rod and to disengage the drum and ride freely over the same when said link rotates the lever arm in the opposite direction, means extending through said slot and engaging the lever arm on the inside of the drum to bias the lower end of said arm in a direction opposite to the rotational direction of said drum, and an adjustable stop disposed to engage the lower end portion of said arm to limit the rotary movement of said drum to regulate the feed of said stoker screw.

3. A pinch clutch stoker drive for driving a shaft from a power source through a reciprocating connecting rod to intermittently rotate a stoker screw, which comprises a sheet metal drum secured to said shaft and having a circumferential slot extending in the circumferential wall thereof, a lever arm secured at the upper end to said reciprocating rod and having the lower end thereof extending into said drum through the circumferential slot therein, a pair of pins connecting the lower end of the lever arm to said drum with the outer pin extending transversely through the arm on the outside of the circumferentially extending drum slot and the inner pin extending transversely through the arm on the inside of said slot, and said outer pin being offset from the inner pin in the direction of movement of said drum to clamp the drum therebetween and rotate the latter when said rod is reciprocated in one direction and to disengage the drum and ride free of the same when said rod is reciprocated in the opposite direction, and a spring extending through the slot in said drum and having one end secured to the lever arm on the inside of the drum and the other end secured to the frame.

of the stoker assembly to bias said arm in a direction opposite to the rotational direction of said drum.

4. A pinch clutch stoker drive for driving a shaft from a power source through a reciprocating connecting rod to intermittently rotate a stoker screw, which comprises a sheet metal drum secured to said shaft and having a circumferential slot extending in the circumferential wall thereof, a lever arm secured at one end to said reciprocating rod and having the other free end thereof extending into said drum through the circumferential slot therein, a pair of pins connecting the free end of the lever arm to said drum with one pin extending transversely through the arm on the outside of the circumferentially extending drum slot and the other pin extending transversely through the arm on the inside of said slot, and said pins being disposed to clamp the drum therebetween and rotate the latter when said rod is reciprocated in one direction and to disengage the drum and ride free of the same when said rod is reciprocated in the opposite direction, a spring secured to the lower end of the lever arm to bias the same in the direction of reciprocation of said rod when the pins ride free of the drum, a second lever arm anchored to the stoker frame at one end and extending into said slot substantially opposite the first mentioned lever arm and connected to said drum by pins extending across said slot on the inside and outside of said drum, said pins being disposed to clamp the drum and prevent rotation thereof when the pins of the first mentioned lever arm ride freely over the drum and to disengage the drum and ride free of the same when the pins of the first mentioned lever arm clamp the drum and rotate the same.

5. A pinch clutch stoker drive for driving a shaft from a power source through a reciprocating connecting rod to intermittently rotate a stoker screw, which comprises a sheet metal drum secured to said shaft and having a circumferential slot extending in the circumferential wall thereof, a lever arm secured at one end to said reciprocating rod and having the other free end thereof extending into said drum through the circumferential slot therein, a pair of pins connecting the free end of the

lever arm to said drum with one pin extending transversely through the arm on the outside of the circumferentially extending drum slot and the other pin extending transversely through the arm on the inside of said slot, and said pins being disposed to clamp the drum therebetween and rotate the latter when said rod is reciprocated in one direction and to disengage the drum and ride free of the same when said rod is reciprocated in the opposite direction, a spring secured to the lower end of the lever arm to bias the same in the direction of reciprocation of said rod when the pins ride free of the drum, a second lever arm anchored to the stoker frame at one end and extending into said slot substantially opposite the first mentioned lever arm and connected to said drum by pins extending across said slot on the inside and outside of said drum, said pins being disposed to clamp the drum and prevent rotation thereof when the pins of the first mentioned lever arm ride freely over the drum and to disengage the drum and ride free of the same when the pins of the first mentioned lever arm clamp the drum and rotate the same.
